UNITED STATES PATENT OFFICE.

PAUL WORTH, OF AKRON, OHIO, ASSIGNOR TO THE INDIA TIRE AND RUBBER COMPANY, OF MOGADORE, OHIO, A CORPORATION OF OHIO.

DESIGN FOR A TIRE TREAD.

Application filed July 10, 1922. Serial No. 3,025. Term of patent 14 years.

To all whom it may concern:

Be it known that I, PAUL WORTH, a citizen of the United States, residing at Akron, in the county of Summit and State of Ohio, have invented a new, original, and ornamental Design for Tire Treads, of which the following is a specification, reference being had to the accompanying drawings, forming a part hereof.

In the drawings Figure 1 is a top plan view of a portion of the tire tread.

Figure 2 is a cross section on the line 2—2 of Figure 1.

Figure 3 is a fragmentary side elevation of a portion of the tire tread. Figure 4 is a fragmentary perspective view thereof.

This application is a substitute for my prior application Serial No. D 1179, filed March 15, 1922.

I claim:

The ornamental design for a tire tread as shown.

PAUL WORTH.
